PATENTED. 1849.

No. 262. Design

(4) Wm. P. Cresson, of Philadelphia, in the County of Philadelphia, State of Pennsylvania, has invented a Design for a Panel - Patent Sch. 5. 1850
Invented Oct. 1. 1849 -

Ms. 162

William P. Brepon, assignee of
Stuart, Brepon & Leibert, all of, Philadelphia, Pa.
Letters Patent No. 262. Dated Feby 5. 1850. antedated Oct 1. 149.

The schedule referred to in these Letters Patent and making part of the same

To whom it may concern:

Be it known that we, Wm. P. Brepon, David

Stuart & Peter Seibert, all of the County of Philadelphia, in the State of Pennsylvania, have invented or produced a new and useful set of designs which are intended to ornament a Stove called a Radiator Screen and do hereby declare that the following is a full and exact description of the same.—

Fig. 1. Represents the bottom or hearth plate which is beautifully carved around the front with a succession of leaves and scroll work as at a. a. a. a. connected with a shell rosette as b. on either side you have the places for the columns with a bead carving as at c. c. c. c. outside of which we have bead work and carving as at d. d. d. d.—

Fig 2. Represents the top plate beautifully carved on the outer edge as at a. a. a. a. a.—

Fig 3. Represents the screen beautifully carved and designed with an entirely new and original design as represented at a. a. a. a. enclosed on either side with scroll work as at b. b. b. b. and at top and bottom is a new style bead work as at c. c. c. c.—

We have thus described the ornamental design which we claim as our invention or production and desire to secure by letters patent the design for a stove called a Radiator Screen herein fully described and represented in the accompanying drawings.—
